UNITED STATES PATENT OFFICE

SIDNEY H. BINGHAM AND ARTHUR C. LE MAIRE, OF NEW YORK, N. Y.

PORTABLE STREET-CROSSING BRIDGE.

Application filed April 14, 1925. Serial No. 22,959.

This invention relates to bridge structures, and particularly portable bridge structures. The object of our invention includes the provision of a portable bridge structure for crossing crowded thoroughfares, car tracks and the like. We further aim to produce a structure that is relatively inexpensive and so constructed as to be adjustable and readily transported from place to place. Our object primarily includes the provision of a safety device to enable pedestrians to safely cross a street at any time without waiting for the clear signal or of being endangered by passing vehicles or trains. Other objects will appear hereinafter, and we attain these objects by the construction illustrated in the accompanying drawings, in which:—

Fig. 1 is a view in elevation showing the bridge structure in position.

Fig. 2 is a side elevation of one of the two complementary members, showing the bridge folded and ready for transportation.

Fig. 3 is a view of the complementary member showing traction means; and

Fig. 4 is a view showing one form of steering means.

Like numerals refer to similar parts throughout the several views wherever they occur.

The danger to pedestrians in crossing crowded thoroughfares is well recognized, and it is our purpose to lessen this danger in a practical and comparatively simple manner. By use of a portable bridge structure of the type herein disclosed, we provide means whereby pedestrians are enabled to proceed on their way and safely cross a street without danger of being struck by an automobile. By providing means for transportation, the structure may be easily and quickly moved to points of greatest congestion and thereby relieve traffic at such points.

In the accompanying drawing, we have illustrated one form of construction which embodies our invention as applied to a portable foot bridge of steel construction, but obviously our invention is not thereby limited to the particular construction shown. As a practical application of our invention, we provide two complementary structures which, for convenience, we will designate the right hand member "A" and left hand member "B" respectively. These members are substantially duplicates of each other, except in certain minor details to be noted

later. A detailed description of all the duplicate parts will therefore not be necessary.

By referring to Fig. 1, it will be noted that the bridge sections 10^a or 10^b are pivotally mounted to swing on uprights or frames 11^a or 11^b, which are appropriately braced by cross beams 12^a or 12^b, reinforcing braces 13^a or 13^b, and the base or chassis frame 14^a or 14^b. The latter carries the truck driving wheels 15^a or 15^b and the guide wheels 16^a or 16^b. The upright frame members, the reinforcing members and the braces are firmly united by the approach stringers 17^a or 17^b on which are provided stair steps 18^a or 18^b and guide rails 19^a or 19^b. Folding steps 20^a or 20^b may be provided to extend to the sidewalk 45^a or 45^b. The bridge members 10^a or 10^b are raised or lowered by arms 21^a or 21^b and cables 22^a or 22^b operating over pulleys 23^a or 23^b, by means of suitable hoisting mechanism 25 which consists of the drive clutch 31 and the worm drive 26 operating in a gear 27. The hoisting mechanism is operated by drive gear 28, or the like, which is driven from a source of power, as a gas engine diagrammatically represented at 29. The engine also provides the motive power for moving the structure through the driving mechanism 30, clutch device 32 and worm drive 33 and 34. This mechanism is controlled by any convenient means, as foot lever 35 and brake lever 36 from the platform 37. The steering is done by means of the steering wheel 38, gear connections 39 and 40, worm gear 41 and 42, to operate the guide wheels 16 through the steering knuckles 43.

It will be noted that levers 35 and 36 and the platform are hingedly joined so as to permit raising and fastening them by a hook 44 and thus providing a passageway when the device is in position on the sidewalk 45^a or 45^b.

To place the bridge structure so as to span a thoroughfare, for example, the two members are wheeled into position with the smaller, or guide, wheel on the sidewalk and the larger, or drive, wheel in or near the gutter. The bridge sections are then hoisted from the position shown in dotted lines and at which position struts 46^a and 46^b hold these sections during transportation. This hoisting is done by means of the hoist 25, described above, which is put into

operation by a control 47, thus raising the respective sections into engaging position so that the notch finger 48 engages the lock rod 49 of the respective sections 10^b and 10^a. Section 10^a is further provided with an overlapping bridge portion 50 to provide a smooth and safe floor. Section 10^a is further provided with a number of differently spaced lock rod ears 51, 52, 53 and 54 for varying widths of crossings.

Having now described our invention, what we claim as new and useful, of our own invention, and desire to secure by Letters Patent, is:—

15 1. In a bridge structure, a bridge platform, means for supporting said platform, said supporting means including frame members and inclined stringers, steps on said stringers, and means for bodily moving said supporting means and said platform.

20 2. A portable bridge structure comprising complementary bridge members each having an arm extension, supporting members on which said bridge members are mounted to swing, a hoisting device on said supporting members, said hoisting device having a cable attached to the end of said arm for swinging each of said bridge members, and means 25 to transport said supporting members and said bridge members.

30 3. A portable foot bridge structure comprising complementary bridge members each having an arm extension, supporting means including uprights and stringers having a pivot on which each of said bridge members are mounted to swing, means to transport said supporting members and said bridge members, and means attached to said arm 35 extension to hoist and lower said bridge members.

40 4. A portable foot bridge structure comprising complementary bridge members

each having an arm extension, supporting means on which said bridge members are mounted to swing, said means including a chassis having substantially vertically disposed uprights and angularly disposed stringer members uniting the upper ends of the uprights with the removed end of the chassis to form an elevated pivot point for said bridge members, a hoisting device carried by said supporting means, and extending to said arm extension for controlling the position of each bridge member independently of the other, wheels on said supporting means for moving the same, and means to guide one or more of said wheels.

45 5. A portable bridge structure comprising complementary bridge members, supporting members on which said bridge members are mounted to swing, wheels on said supporting members to move said members from place to place, said supporting members having inclined stringers, and steps on 50 said supporting members for crossing the bridge formed by joining said complementary members.

55 6. A portable foot bridge structure comprising complementary bridge members each 55 having an arm extension, supporting members on which said bridge members are mounted to swing, a hoist device reaching from said supporting members to said arm extension whereby each of said bridge members is moved, hook devices on one of said complementary bridge members, and lock rods on the other of said members to thereby secure said complementary members together.

60 In testimony whereof we have hereunto set our hands on this 8th day of April A. D., 1925.

SIDNEY H. BINGHAM.
ARTHUR C. LE MAIRE.
